MANUALLY SET LOCKING DEVICE

Robert L. Stratton, Folcroft, Pa., assignor to
 I-T-E Circuit Breaker Company, Philadelphia,
 Pa., a corporation of Pennsylvania

Application November 10, 1951, Serial No. 255,860

5 Claims. (Cl. 317—55)

1

My present invention relates to circuit breaker locking devices and more particularly it relates to manually operated locking devices that lock circuit breakers in the open position.

Their necessity arises from the fact that after a fault has occurred in the circuit protected by the circuit breaker and the circuit breaker has opened the fault current, the circuit breaker could accidentally be closed, producing damage to the electrical equipment connected to the circuit and in case the fault is being repaired, considerable harm to the repair crew.

To avoid any possible harm to operators and equipment, it is not only necessary to maintain open the circuit of the closing relay of the circuit breaker but also to lock the circuit breaker closing solenoid with the circuit breaker contacts in the open position and the door or enclosure in the closed position. This ensures that even if the closing relay should accidentally be energized, the solenoid will not be able to move and thus close the circuit breaker contacts so as to energize the fault current.

To minimize the possibility that operators can manually close the circuit breaker of a fault line, the door giving access to the circuit breaker manual operating mechanism should also remain closed, or still better, locked in the closed position by a number of padlocks.

To be really effective a protective locking device for circuit breakers should incorporate all of these above features; it should also be easy to operate manually from the outside and above all its operation should not present any danger to the operator.

My present invention contemplates a manually operated cylindrical shaft carrying a cam and a lever. The cam operates a spring biased pin which after the opening stroke of the circuit breaker may be used to engage a slot machined in a shaft which is a part of the circuit breaker closing mechanism, thus locking the solenoid in the open position.

As the cam operates the pin to lock open the closing solenoid, the lever strikes a set of normally closed switch contacts in the circuit of the circuit breaker closing relay, thus opening the circuit of the circuit breaker closing relay. Once the shaft has rotated the amount necessary to perform the above-described operation, the handle of the operating shaft can be pivoted to engage a slot in the frame of the circuit breaker, thus locking the shaft in its final position.

Padlocks placed in an appropriate slot of the operating shaft handle serve not only to en-

sure that the shaft and the handle remain in that final position but also that the door or cover of the circuit breaker remains closed.

Furthermore, the provision that a plurality of padlocks, for example three, be used to lock the circuit breaker open ensures that all workers having the necessary padlock keys must be present at the same time in order to unlock the circuit breaker. This makes impossible the accidental unlocking of the circuit breaker by one of the workers while the others are repairing the fault that caused the circuit breaker to open.

Accordingly, an object of my invention is to provide safety facilities in the operation and maintenance of the circuit breaker and its associated electrical system whereby a man or men working on said system at a point remote from the circuit breaker may be assured that the circuit breaker cannot be closed either manually or electrically. This is accomplished by the use of padlocks issued to each man working on the system which may be energized by the closing of the circuit breaker.

Another object of my present invention is, therefore, a locking device that will lock a circuit breaker in the open position, that will maintain the circuit breaker closing circuit electrically inoperative and will keep the door or cover of the circuit breaker mechanically closed.

A further object of my invention is the provision of means whereby this locking device for circuit breakers can be easily and safely operated from the outside, without opening the protective door or cover of the circuit breaker, thus avoiding any possible harm to the operators.

These and other objects of my invention will become apparent in the following description when taken together with the drawings in which:

Figure 1 is a plan view of the locking device of my invention shown with the circuit breaker in the closed position.

Figure 2 is a front view of the locking device of my invention shown with the circuit breaker in the closed position.

Figure 3 is a plan view of the locking device of my invention shown with the circuit breaker in the open position.

Figure 4 is a front view of the locking device of my invention shown with the circuit breaker in the open position.

Figure 5 is a detail view of the closing relay switch used in my invention.

Figure 6 is a perspective view of a circuit breaker incorporating my novel locking device.

Figure 7 is a wiring diagram of the circuit breaker incorporating my invention.

Referring first to Figure 6 showing a three-pole circuit breaker incorporating my present invention, circuit breaker 50 is mounted on a vertical support 51 and a horizontal base 52 by any suitable means.

Circuit breaker 50 is provided with three movable contacts 53 which engage in the circuit breaker closed position their corresponding stationary contacts (not shown). An arc chute 55 placed around the stationary contacts (not shown) serves to extinguish the arc that would exist between movable contacts 53 and the stationary contacts (not shown) at the circuit breaker opening operation.

The three movable contacts 53 are tied together by means of a tie bar 56. Tie bar 56 makes possible the simultaneous operation of the three movable contacts 53 so that if a fault should occur in the line connected to pole 53a not only will movable contact 53a move to the open position but together with 53a movable contacts 53b and 53c.

Movement of tie bar 56 leads to vertical movement of cylindrical rod 58 through the toggle mechanism generally referred to as 60. Cylindrical rod 58 is rigidly secured to a rectangular section block 62 carried on a shaft 63 rotatable in bearings 64 of arms 65 of connecting link 68. Connecting link 68 carries at its end 70 a shaft 101 so that a rotation of link 68 in one direction produces a similar rotating movement of shaft 101.

A spring 72 secured at one end to post 75 and at its other end to link 68 serves to bias link 68 toward post 75 and, therefore, to bias through rod 58 toggle 60 in the circuit breaker closed position.

When the circuit breaker 50 opens because of a fault, toggle 60 will break, moving rod 58 upwardly and producing a clockwise rotation of link 68 under the bias of spring 72.

Since, as previously mentioned, shaft 101 is rigidly secured to link 68, shaft 101 will also rotate in a clockwise direction if link 68 rotates in a clockwise direction.

It is thus seen that when circuit breaker 50 is tripped open, shaft 101 rotates in a clockwise direction for a certain number of degrees. It is also quite evident that the trip open operation can also be performed manually through appropriate mechanisms (not shown).

When, on the other hand, the circuit breaker 50 is to be closed, a crank (not shown) can be secured to shaft 101 to rotate shaft 101 in the counterclockwise direction in this particular embodiment of my invention.

When shaft 101 rotates in the counterclockwise direction, link 68 will also rotate in the same direction against the bias of spring 72, pulling down rod 58, re-establishing toggle 60 and, therefore, moving the movable contacts 53 in current carrying engagement with the stationary contacts (not shown).

In order to make possible such a rotation of shaft 101, it is necessary that shaft 101 be provided with and be rotatable into a stationary bearing 71. Bearing 71 is secured to angle post 75 by means of nuts and bolt means 76.

Referring now to Figures 1 and 2 showing the locking device of my invention in a detail view and in the open position, circular shaft 101, as previously mentioned, forms a part of the closing mechanism of the circuit breaker 50. Shaft 101 rotates in one direction around its longitudinal axis by 90° during the closing stroke of the circuit breaker and remains in that position while

the circuit breaker remains in the closed position. When, on the other hand, the circuit breaker is tripped open, the shaft 101 rotates in the opposite direction by 90° to take the position shown in Figures 3 and 4.

A disc 102 of some thickness is mechanically fastened to shaft 101 so that it rotates together with shaft 101. Through this disc 102 a slot 103 is machined (Figures 2 and 4). Disc 102 is so fastened on shaft 101 that slot 103 is so located as to cooperate properly with respect to the other parts of the locking device. More precisely, slot 103 is so located that when the circuit breaker is tripped, slot 103 moves exactly opposite shoulder pin 104 to receive shoulder pin 104.

Shoulder pin 104 has two aligned cylindrical extensions 105 and 106. Extension 105 extends to the left (see Figures 1, 2, 3 and 4) of shoulder 107 of pin 104 and extension 106 extends to the right of shoulder 107 of pin 104.

Shoulder pin 104 is partly housed in structure 108 having a removable side plate 109 secured to structure 108 by means of screws 110 engaging appropriate threaded bores 111 in opposite side plate 112 of structure 108. Side plate 109 has an opening 113 aligned with another opening 114 in side plate 112.

Openings 113 and 114 are large enough to allow extensions 105 and 106, respectively, of pin 104 to move freely through them. Shoulder pin 104 is biased away from engagement with slot 103 of disc 102 or toward the position where shoulder 107 of pin 104 rests against the side plate 112 by means of compression spring 115 located between side plate 109 and shoulder 107 of pin 104 as shown in this preferred embodiment or by any other appropriate biasing means.

Structure 108 is carried through bolts 116 and nuts 117 by an angle 118 rigidly connected to the supporting angle 75 of the circuit breaker 50 by means of bolts, nut and washer means 76.

On the same angle 118 is also mounted by means of bolts 123 and nuts 124 a normally closed switch 125, hereinafter described in connection with Figure 5, whose contacts (see Figure 7) are connected in series with the closing switch 126 and pick-up coil 127 of the closing relay 128 of the circuit breaker 50.

In the circuit breaker "open" position as shown in Figures 3 and 4, extension 106 bears against a cam 129. Cam 129 is eccentric for this preferred embodiment, but otherwise of any suitable shape, and is secured by key 130 to an operating shaft 131 axially rotatable in bearing 132. Bearing 132 cylindrical shape has a closed end slot 133 and is attached to the door or cover 134 by a set of screws 135 engaging appropriate threaded bores in bearing 132.

To the same shaft 131 are fastened a lever 136 and a handle 137 by means of keys 138 and 139, respectively. The handle 137 has a latch 140 loosely pivoted around pivot point 141. Latch 140 is equipped with a slot 142 which can accommodate a number of padlocks, for example three (not shown). The latch extension 143 of latch 140 can mesh with the closed end slot 133 in bearing 132 when the handle 137 is turned 90° in clockwise motion from the positions shown in Figures 1 and 2. Operating shaft 131 in this particular embodiment is enclosed in a cylindrical sleeve 144.

When the circuit breaker is tripped open, shaft 101 as previously shown rotates clockwise 90° to take the position shown in Figures 3 and 4. Therefore, disc 102 also rotates by 90° moving

slot 103 exactly opposite extension 105 of pin 104 ready to receive extension 105.

The operator now rotates the handle 137 by 90° clockwise, thus rotating also operating shaft 131 by 90° clockwise around its longitudinal axis.

The keyed cam 129 and lever 136 rotate together with shaft 131, thus performing the following operations:

Cam 129 bearing against extension 106 of shoulder pin 104 pushes extension 105 of shoulder pin 104 against the bias of spring 115 into engagement with slot 103 of disc 102 of the closing mechanism of the circuit breaker 50, thus mechanically blocking any rotation of shaft 101 of the closing mechanism.

Lever 136 pushes rod 145 which controls the normally closed switch 125. Switch 125, shown in detail in Figure 5, as previously mentioned is connected in series with the closing relay 128 (see Figure 7). More specifically, switch 125 is provided with two stationary contacts 150 and 151 both secured to housing 158 of switch 125 in any suitable manner.

Contact 151 is connected to closing relay 128 while contact 150 is connected to control switch 126. Contacts 150 and 151 are normally bridged by a shorting bar 152 carrying two button contacts 153 and 154 in alignment with stationary contacts 150 and 151.

Shorting bar 152 is rigidly secured and movable with the operating rod 145 which extends in one direction through plate 157 of switch housing 158 and at whose end there is a larger diameter portion 160. The other end 161 of rod 145 extends beyond shorting bar 152 and on it is placed a compression spring 163 which biases shorting bar 152 and, therefore, movable contacts 153 and 154 against stationary contacts 150 and 151, respectively.

When lever 136 strikes larger diameter section 160 of rod 145, rod 145 will be pushed against the bias of spring 163 to produce the opening operation between movable contacts 153 and 154 on one side and stationary contacts 150, 151 on the other side, thus interrupting the circuit between closing relay 128 (see Figure 7) and the control switch 126, thus rendering circuit breaker 50 electrically inoperative.

Lever 136 rotated by means of handle 137 also serves to keep door 134 of switch 50 mechanically locked in the closed position since lever 136 after the above-described rotation of handle 137 will be located behind the stationary bracket 118. In other words, when lever 136 has been rotated so as to be behind bracket 118, the door 134 cannot be swung open to afford undesirable accessibility to the circuit breaker closing means which, as previously described, could, for example, be a crank (not shown) engaging shaft 101 of circuit breaker 50.

At the end of this rotation of handle 137, handle 137 is so positioned (Figures 3 and 4) that latch 140 can be pivoted and the latching extension 143 embedded in the slot 133 of bearing 132.

A number of padlocks, for example three, (not shown) may be set into the slot 142 of latch 140 to lock the circuit breaker 50 mechanically open and the closing relay coil 128 electrically open.

The use of a relatively large number of padlocks, three in this example, all having different keys is necessary in that it prevents accidental opening of the circuit breaker 50 while one of the holders of one key of one padlock is working on the circuit connected to circuit breaker 50, for example, if the circuit breaker 50 had tripped

open because of a fault and the operator had turned handle 137 to lock the circuit breaker in this open position.

Assuming that a number of people who are in charge of circuit breaker 50 are three, three padlocks having each a different key are now placed in slot 142 and one key is given to each man.

It is now evident that if one of these three men is repairing a fault, no one else can accidentally close the circuit breaker in that access to the manual closing means will be prevented by the existence of these padlocks and even if one of the holders of such keys does open one of these padlocks, since the other padlocks are still in slot 142, it is obvious that he will not be able to rotate handle 137 to open door 134 of circuit breaker 50 to close the circuit breaker.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. In a circuit breaker having operating means comprising a normally closed switch and a closing relay coil, said switch for interrupting the circuit of said closing relay coil; a rotatable bar, said bar being axially rotatable, a slotted disc, said disc being fastened to and being rotatable with said bar, said bar rotating in one direction during the opening stroke and in the opposite direction during the closing stroke of said circuit breaker, a manually operated shaft, a bearing, said shaft rotating in said bearing, said shaft having a cam and a lever; said cam and said lever rotating with said shaft; a pin; said pin being biased against said cam, said shaft rotating said cam; said cam driving said pin into engagement with said slot of said disc after the opening stroke of said bar, said shaft also rotating said lever, said lever operating said normally closed interrupting switch, said bearing having a recess; said shaft having a handle on the side opposite said cam and lever, said handle comprising a loosely pivoted latch, said latch being engageable with said recess of said bearing at the end of rotation of said shaft; means locking said handle and shaft; said circuit breaker including a door; said door being locked in the closed position by said locking means.

2. In a circuit breaker having operating means comprising a normally closed switch and a closing relay coil, said switch for interrupting the circuit of said closing relay coil; a rotatable bar, said bar being axially rotatable, a slotted disc, said disc being fastened to and being rotatable in said bar, said bar rotating in one direction during the opening stroke of said circuit breaker, a manually operated shaft, a bearing, said shaft rotating in said bearing, said shaft having a cam and a lever; said cam and said lever rotating with said shaft; a pin; said pin being biased against said cam, said shaft rotating said cam; said cam driving said pin into engagement with said slot of said disc after the opening stroke of said bar, said shaft also rotating said lever, said lever operating said interrupting switch; said bearing having a recess; said shaft having a handle on the side opposite said cam and lever, said handle comprising a loosely pivoted latch, said latch being engageable with said recess of

said bearing at the end of rotation of said shaft; means locking said handle and shaft.

3. In a circuit breaker comprising a pair of cooperable contacts, linkage mechanism, a closing relay coil, a normally closed switch, and a spring biased pin; said cooperable contacts having an engaged and disengaged position, said linkage mechanism having a first and second position corresponding to said engaged and disengaged positions, respectively, of said cooperable contacts; said normally closed switch positioned in series with said closing relay coil, said linkage mechanism comprising a rotatable bar and a slotted disc, said rotatable bar being axially rotatable and having said slotted disc fastened thereto for rotation therewith, said rotatable bar rotated in a first direction during the movement of said circuit breaker from contact engaged position to contact disengaged position, manually operable means comprising an operated shaft, a cam and a lever; said cam and said lever attached to said operated shaft and rotatable therewith, said spring biased pin biased against said cam, said operated shaft when manually rotated from a first to a second position causing said cam to drive said pin into engagement with said slot of said disc when said circuit breaker and said associated linkage mechanism are in contact disengaged position, said operated shaft when manually rotated from said first to said second position rotating said lever into engagement with said normally closed switch to thereby interrupt the circuit to said closing coil, said bar having a recess, said operated shaft having a handle on an end opposite said cam and lever, said handle comprising a loosely pivoted latch, said latch being engageable with said recess of said bar when said shaft is rotated to said second position, said latch being locked in said engageable position to thereby lock said handle to said operated shaft.

4. In a circuit breaker comprising a pair of cooperable contacts, linkage mechanism, a closing relay coil, a normally closed switch, and a spring biased pin; said cooperable contacts having an engaged and disengaged position, said linkage mechanism having a first and second position corresponding to said engaged and disengaged positions, respectively, of said cooperable contacts; said normally closed switch positioned in series with said closing relay coil, said linkage mechanism comprising a rotatable bar and a slotted disc, said rotatable bar being axially rotatable and having said slotted disc fastened thereto for rotation therewith, said rotatable bar rotated in a first direction during the movement of said circuit breaker from contact engaged position to contact disengaged position, manually operable means comprising an operated shaft, a cam and a lever; said cam and said lever attached to said operated shaft and rotatable therewith, said spring biased pin biased against said cam, said

operated shaft when manually rotated from a first to a second position causing said cam to drive said pin into engagement with said slot of said disc when said circuit breaker and said associated linkage mechanism are in contact disengaged position, said operated shaft when manually rotated from said first to said second position rotating said lever into engagement with said normally closed switch to thereby interrupt the circuit to said closing coil, said bar having a recess, said operated shaft having a handle on an end opposite said cam and lever, said handle comprising a loosely pivoted latch, said latch being engageable with said recess of said bar when said shaft is rotated to said second position, said latch being locked in said engageable position to thereby lock said handle to said operated shaft.

5. In a circuit breaker for protecting an electric unit, a pair of cooperable contacts having a contact engaged and a contact disengaged position, a manually operable handle, a linkage extending from said handle to said contacts and having a contact engaged position and a contact disengaged position; said handle having a contact engaged and a contact disengaged position, means including said handle and electromagnetic means responsive to a fault current in said electric unit for effecting operation of said contact to disengaged position, said linkage effecting engagement of said cooperable contacts, a lock mechanism having one part controlled by the operation of said contacts to disengaged position and a second part operable by said handle when said handle is operated to its second position, said parts interlocking to lock said contacts and linkage in contact disengaged position and a lock mechanism for locking said handle in its second position; electromagnetic mechanism; a circuit for energizing said electromagnetic mechanism for operating said contacts to engaged position and contacts in said circuit locked open under control of said handle in its second position for rendering said electromagnetic mechanism non-energizable to operate said contacts into engagement.

ROBERT L. STRATTON.
